Primary Examiner — Charles D Hanson(74) Attorney, Agent, or Firm — Pearne & Gordon LLP(57) CLAIM

The ornamental design for a shaving brush container, as shown and described.

DESCRIPTION

FIG. 1 is a perspective view of a shaving brush container, showing my new design;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

The material shown in broken lines is for illustrative purposes only and forms no part of the claimed design.
